(57) **CLAIM**

The ornamental design for a light fixture, as shown and described.

DESCRIPTION

FIG. 1 is an isometric view of the light fixture of the present design;

FIG. 2 is a front elevation view thereof;

FIG. 3 is a top plan view thereof;

FIG. 4 is a bottom plan view thereof;

FIG. 5 is a right side elevation view thereof, the left side elevation view being a mirror image thereof; and,

FIG. 6 is an enlarged fragmentary view of the light modifier portion thereof.

The broken line shown is for illustrative purposes only and forms no part of the claimed invention.
